UNITED STATES PATENT OFFICE.

WALLACE M. WEEKS AND JOHN A. PEASE, OF SKANEATELES, NEW YORK.

BOTTLE CLOSURE.

Application filed August 31, 1925. Serial No. 53,689.

This invention relates to improvements in bottle caps, designed particularly for closing and sealing the mouths of ordinary milk bottles, and has for its object to provide a normally flexible paper closure, which consists of a disc-shaped central body adapted to be seated upon the annular ledge that forms the bottom of the recess of the bottle mouth, and an integral flaring collar or flange, which is arranged to unfold and overlie and conform to the flared portion of the bottle mouth, when the disc is forced into the said recess; the said collar adjacent its base being folded inwardly parallel to the disc for providing an annular socket to receive the peripheral margin of a circular reinforcing member of thicker gage and of less flexibility than the cap; the portions of the disc and reinforcing member that lie within the inner circumference of the annular ledge being correspondingly dished by the use of molding dies, and the peripheral margins of the disc and member comprising similar plane flanges that conform to and rest upon said annular ledge. This concave formation prevents the air which is compressed in the void between the liquid contents of the bottle and the cap during the capping operation, from lifting the cap and breaking the seal, following the relaxing of the pressure exerted during the capping. By forming the central portions of the cap and reinforcing member concave, and the concave being positioned below the plane of the annular ledge, any upward flexing of the cap and reinforcing member by the compressed air, or by the contents of the bottle in case the latter should be tilted or inverted, tends to expand the said parts radially, thereby increasing their diameters, and effecting a tightening of the grip of the cap with the walls of the recess above the annular ledge. By materially increasing the thickness of the reinforcing member, we are able to employ lighter weight paper for the main cap, which not only facilitates the die-work by which the caps are formed, but renders the unfolding of the collar and its conformity to the flaring mouth of the bottle more readily effected.

This invention relates particularly to improvements in the bottle cap shown and described in Letters Patent No. 1,460,269, dated June 26, 1923.

We attain these objects by the means set

forth in the detailed description which follows, and as illustrated by the accompanying drawing, in which—

Figure 1 is a central vertical section; 60 showing the cap applied to a milk-bottle; a portion of the bottle being shown in section. Fig. 2 is a similar sectional view of the cap in the collapsed state. Fig. 3 is a top-plan view of the cap shown in Fig. 2. 65 And Fig. 4 is a top-plan view of the reinforcing member.

In the drawing, 2 represents the neck of an ordinary milk-bottle. 3 is the flaring mouth of the bottle, and 4 indicates the annular ledge or shoulder, which forms the bottom of the recess in which the closure is usually disposed.

Our improved bottle closure comprises a disc-shaped body 5, whose diameter substantially equals that of the recess and the ledge 4, to which is integrally joined a relatively broad flexible collar or flange 6. At its juncture with the disc 5 the collar 6 is first folded inwardly parallel to the peripheral margin of the disc, for providing an annular socket or groove 6', after which the free margin of the collar is folded outwardly upon itself, for providing an annular convex portion 6^a of greater diameter than the disc 5. The cap 5 is preferably made from flexible paper of relatively light gage, which may be readily folded and molded, as shown in Figs. 2 and 3, by means of suitable dies, and whose flange 6 may be readily unfolded and flared when the cap is applied to the bottle mouth, as shown in Fig. 1. The disc 5 is preferably depressed or dished, as at 5^a, to the extent of the clear opening of the neck below the plane of the ledge 4, for stiffening the disc and for resisting upward or outward flexing of the disc by the contents of the bottle, or by the expansion of air, which is usually confined in the void, as 2', by the quick and forcible insertion of the closure, as shown in Fig. 1. This dishing of the disc 5 may be effected by the dies that are employed for forming-up the cap, and is preferably performed in a manner to provide a plane annular margin or flange 5^b, for affording a firm and continuous seating upon the ledge 4. The main cap, owing to the light gage of the material, requires reinforcing in order to prevent its disc-shaped body from being unduly flexed or distorted during the capping operation. To this end, we provide a circular member 7, which may

be made from card or tag board, and whose gage is preferably considerably greater than the gage of the disc 5. The diameter of the member 7 should be substantially equal to 5 the diametric dimension of the socket 6', so as to suitably reinforce the inward fold 6^b of the collar, for preventing collapse or distortion of the margin 6^c (see Fig. 1) which frictionally engages the walls of the recess. 10 The central portion 7' of the member 7 is correspondingly depressed and overlies intimately the top face of the disc 5, and the peripheral margin of said member beyond the depression 7', also comprises a plane 15 flange 7^a, which closely contacts with the flange 5^b and extends into and gages the depth of the socket 6', by which the member 7 is held in place, as shown in Figs. 1 and 2. In practice, the cap 5 and the reinforcing 20 member 7 are stamped from flat sheets of paper, which are usually saturated with paraffin. The member 7 is next mounted concentrically upon the cap, and the two parts are then placed between the dies for 25 effecting the folding and dishing of the parts. When this work is properly done, the member 7 substantially fills and is firmly held by the groove 6', and when the flange 6 is later unfolded, by the insertion of the 30 cap in the flaring mouth 3, the peripheral edge of said member will still be gripped by the top wall of said groove, for holding the cap and member interlocked, as shown in Fig. 1. By this construction and arrangement, 35 the cap and reinforcing member 7 supplement each other for maintaining the concave formation of the central body portions, and for effectively sealing the bottle mouth, and any outward pressure exerted either by 40 the liquid contents of the bottle, or by the air that may be compressed between the cap and the liquid during the sealing of the

mouth of the bottle, cannot effect the unseating of the cap. The value of the concave or dishing feature of the present closure 45 will be appreciated when it is understood that, caps constructed according to the former patent referred to, frequently become loosened and unseated, especially when roughly handled, due to the pressure of the 50 air confined in the void 2' below the annular ledge 4, as explained. This accidental unseating of the cap is effected more readily, by reason of the fact that the recess of the bottle neck is usually wet and rendered slippery by the spraying of the milk during the 55 filling of the bottle, which destroys the frictional adhesion of the cap to the walls of the recess.

Having thus described our invention, 60 what we claim, is—

As a new article of manufacture, a bottle closure comprising a thin body having a curved marginal part to fit over the bead of the bottle mouth and a permanently concaved bottom, a permanently concaved thick reinforcing member of equal thickness and diameter having a plane annular flange with a continuous circular peripheral edge conforming to and seated on said concave bottom of the body, said body having the inner portion of its curved margin folded inwardly and upon the upper face of the plane flange of the reinforcing member to hold same in tight and close engagement 65 with the concaved bottom, the said folded part of the body forming an abutment whereby to hold the flange of the reinforcing member against upward movement upon 70 upward flexure of the bottom.

In testimony whereof we affix our signatures.

WALLACE M. WEEKS.
JOHN A. PEASE.
